CLAIM

The ornamental design for a magnetically suspended cross, as shown.

DESCRIPTION

FIG. 1 is a perspective view of a magnetically suspended cross showing my new design;

FIG. 2 is a top plan view of my magnetically suspended cross;

FIG. 3 is a front view of my magnetically suspended cross, the front view being identical with the rear view; and,

FIG. 4 is a right end view of my magnetically suspended cross, the left end view being identical with the right end view.
